Charles Kirchhof,

UNITED STATES PATENT OFFICE.

CHARLES KIRCHHOF, OF NEWARK, NEW JERSEY.

ALARM CHIME-BELLS FOR HORSES.

Specification forming part of Letters Patent No. 10,108, dated September 29, 1863.

To all whom it may concern:

Be it known that I, CHARLES KIRCHHOF, of the city of Newark, county of Essex, and State of New Jersey, have invented a Chime-Alarm for Horses; and I do hereby declare that the following is a full and exact description thereof, reference being had to the accompanying drawings, and to the letters of reference marked thereon, in which—

Figure 1 represents a front view of a device illustrating the application and combination of the principal parts of my invention. The others figures from 2 to 10 are sketches representing a variety of modifications and combinations which can be made by means of these parts.

The nature of my invention consists in constructing an alarm for horses, made of ordinary clock or similar-shaped bells, differing from similar alarms in its peculiar construction, superiority, and merits of the former. I attach my chime alarm to any horse independent without any alteration or additional preparation of the harness. It also gives a most unique appearance, and by the peculiar arrangement of the clappers and its construction it produces a continued harmonic sound.

To enable others skilled in the art to make and use my invention, I will proceed to describe its construction and operation.

In order to connect the bells and clappers easy and convenient with each other and properly to the horse, I use one or more contrivances consisting of two parts. One part is for supporting the bells and other devices subsequently described, and the other part, in connection with the first part, is to attach and secure it properly on or above the back or about the horse, and consists of a girdle-belt, cushion with a belt, or any means that will answer to attach it independent from the harness, as mentioned above.

The first or upper part is made of metal or any suitable material, and consists of one or more stands or of a frame, or any contrivance answering the purpose as required, a variety of which will be shown under letters *a a* in all the figures. The upper portion of each is for arranging and attaching the bells and their combinations thereupon, and the lower portion, forming the stand supporting the combination, is constructed as to be placed properly upon and about the horse by

means of the lower part connected with it. To avoid the interference of the reins, (Figs. 1 and 6, *d d'*, or their equivalents,) I provide the stand with rein-rings or equivalents, as shown in the figures. In consequence of this arrangement the contrivance may be designed and ornamented at will, and constructed in such a manner as to produce the desired effect. Bells of any shape, *b b'*, or similar devices, *e e*, giving a continued sound by each stroke of the hammer, may be fastened and combined with their arrangements in any way, and properly placed and supported to remain in the required position, proportion, and distance relative to each other, and also to the horse.

To obtain the peculiar harmonic prolonged sound, I use springs *s s s v v v*, or other vibrating devices and materials to the combination, either for connecting the hammers *w w*, as shown in Fig. 4, or the bells, Fig. 1, *b' s*, or both, with each other and also with the contrivance *a a*, or I make the whole contrivance, Fig. 6, *a s*, or parts thereof, of springs, or any equivalent, or I use both ways for the purpose of continuing the oscillations and the operation of the clappers to this effect. I also use springs or devices of any desired form, Figs. 1, 3 *v v*, to limit the motion of the clappers *w w*, and to prevent the latter from tilting over and interfering with each other. Further, I place a number of hammers or clappers, by means of their springs, near or around the periphery, Fig. 1, or the inner border, Fig. 2, of each bell, as represented, or I suspend and construct clappers on a rosette, star, ring, or any other device, Fig. 3, and make the arrangements similar in hanging the clappers around the outside of the bell to obtain a loud, continued sound.

The combination of the bells with the clappers I can make in such a manner either that each clapper strikes in turn against more than one bell, as represented in Fig. 5, or I place the bells so over, in, or close to each other that the clapper when oscillating strikes them alternately to obtain an alternate change of the harmony.

I am aware that alarms for horses exist with more or less bells, with two or more clappers inside of the bells, which, by the connection of a bow or similar fixture, are fastened to the saddle, either by means of the rein-rings or screws, or upon a halter prepared for that pur-

pose. Such method of attaching, and the ringing of the bells in that way, I do not claim in my invention.

What I claim as my invention, and desire to secure by Letters Patent, is—

1. The contrivance *a a*, or its equivalent, to attach and support on or above the horse a number of bells and clappers, or their respective equivalents, connected with each other and with the contrivance, in the manner and for the purpose as specified.

2. The combination of rein-rings, or equivalents, with said contrivance, as set forth.

3. The method to produce a peculiar, harmonic, prolonged alarm by governing and extending the operation of the hammers or clappers and bells by means of springs or vibratory materials, and by other devices described, and the manner in which these different parts are arranged and combined with each other, and also with the contrivance *a a*, as specified herein.

CHARLES KIRCHHOF.
